ERIC SODERGREN, OF SIERRA MADRE, CALIFORNIA

REGULATOR FOR WINDOWS AND DOORS

Application filed July 16, 1927. Serial No. 206,244.

My invention relates to and has for a purpose the provision of a regulating device particularly adapted, although not necessarily for casement windows and doors, and which, 5 when in applied position acts to firmly hold the window or door in closed or open positions against movement under the action of wind, yet permitting manual adjustment of the window or door at will.

10 A further purpose of my invention is the provision of a regulating device of the above described character which embodies friction means acting constantly to resist movement of the window or door with which it is associated, yet yielding to manual pressure applied to the window or door to permit adjustment thereof at will, the device embodying fastening means by which the friction means can be rendered effective to securely fasten 15 the window or door in the selected position of adjustment.

20 I will describe only five forms of regulating devices embodying my invention and will then point out the novel features thereof in 25 claims.

In the accompanying drawings,

Figure 1 is a fragmentary view showing in side elevation one form of regulating device in applied position to a casement window, 30

Figure 2 is a sectional view on the line 2—2 of Figure 1 and looking in the direction of the arrows;

Figure 3 is an enlarged vertical sectional view of the holding means embodied in my invention;

Figure 4 is a view similar to Figure 2 and illustrating another form of regulating device embodying my invention;

Figure 5 is a fragmentary view showing in side elevation a third form of regulating device in applied position to a door;

Figure 6 is a sectional view on the line 6—6 of Figure 5 and looking in the direction of the arrows;

Figure 7 is a view similar to Figure 1 and illustrating a fourth form of regulating device in applied position to a casement window;

Figure 8 is a sectional view taken on the line 8—8 of Figure 7.

Figure 9 is a view similar to Figure 7 and illustrating a fifth form of regulating device in applied position to a casement window;

Figures 10 and 11 are enlarged views showing in side elevation and vertical section, respectively, the holding means embodied in the form of my invention illustrated in Figures 8 and 9;

Figure 12 is a sectional view taken on the line 12—12 of Figure 11 and looking in the direction of the arrows.

Reference will now be had specifically to the accompanying drawings, in which similar reference characters designate similar parts in each of the several views, and particularly to Figures 1 to 3, inclusive, which illustrate a form of my invention intended for use at the upper end of a conventional casement window W mounted on hinges 10 for swinging movement in a window frame F, so as to open inwardly of a room.

Common to all forms of my invention, I provide a guide member M in the form of a rectangular-shaped bar which in the present instance is secured at its ends by means of brackets 10a to the top rail 11 of the window so as to be disposed horizontally at the outer side of and in spaced relation to the window.

The member M forms a track for a holding element E and in the present instance the element comprises a rectangular body 12 slotted horizontally to receive the member M between a shoe 13 and a wear plate 14, the shoe and plate having at their ends lateral projections 15 and 16, respectively, which prevent longitudinal displacement of the two from the body 12.

The body 12 is also bored vertically to provide a pocket 17 in which is received an expandable coil spring 18. The spring is interposed between washers 19 and 20 and normally urges the latter washer into engagement with the shoe 13 so as to cause the shoe to set up friction to resist sliding movement of the element E along the member M, the amount of friction being regulated by means of a set screw 21 threaded into the body 12 from its under side and bearing

against the washer 19 so that by adjusting the screw, the tension of the spring can be varied at will to accordingly vary the friction.

Projecting from the outer side of the body 12 is a pair of spaced ears 22 to which is pivotally connected at 23 one end of a rigid rod 24, the other end of the rod being pivotally connected at 25 to a bracket 26 secured to the underside of the top rail 27 of the window frame F.

In operation, it will be clear that through the medium of the holding element E and rod 24, movement of the window will be frictionally resisted and that by suitably adjusting the set screw 21 sufficient friction can be set up to prevent movement of the window under the action of the wind, yet permitting manual movement of the window at will, so that the window can be opened or closed and when released will be releasably held against movement.

It is sometimes desirable to limit the opening movement of the window so as to prevent the latter from striking and possibly damaging articles of furniture in the room, and for this purpose an adjustable stop 28 adapted to be engaged by the element E is slidably mounted on the member M and is adapted to be clamped to the member in a selected position of adjustment, by means of a set screw 29.

It will be noted that when the window is closed the rod 24 forms an acute angle with the member M so that the element E will be immediately effective to resist opening movement of the window, as such movement will simultaneously tend to slide the element along the member. As the acute angle increases during the opening movement of the window, it will be clear that the element will be effective to resist movement of the window regardless of its position of adjustment.

Referring to Figure 4, I have herein shown a second embodiment of my invention intended for use on inwardly opening casement windows having a curved or semi-circular top, which would render it impossible to apply the form shown in Figures 1 to 3, inclusive, at the top of the window and also at its lower end unless the bracket 26 were modified to accommodate the inclination of the window sill.

In the form shown in Figure 4, the member M' is of less length than the member M and is secured by brackets 10b to the inner side of the lower rail 30 of the window. This form of my invention is otherwise identical to the form shown in Figures 1 to 3 with the exception that an elongated bracket 26a projecting outwardly from and secured to the window frame is substituted for the bracket 26, the rod 24a being pivotally connected at one end to the bracket at 25a, so that the rod will be disposed at an acute angle for the purpose previously described.

The embodiment of my invention shown in Figures 5 and 6 is particularly adapted for use on doors, and comprises a member M2 secured in horizontal position by means of brackets 10c to a door D adjacent its upper edge, the holding element E2 being identical in construction to the element E with the exception that a pair of springs 18b are employed for urging the shoe 13b into frictional engagement with the element E2. The rod 24b is pivotally connected at one end to a lug 22b projecting from the element E2 and at its other end to an L-shaped bracket 26b secured to the door frame F' as illustrated, this form of connection between the rod and bracket permitting the door to be swung 180° from closed position so that the door can be fully opened, and frictionally held against movement by the element E2 in any position to which it is manually adjusted.

The embodiment of my invention shown in Figure 7 and 8 is particularly adapted for use on casement windows which open outwardly, the member M3 being secured by brackets 10d to the lower rail of the window at its inner side and the rod 24c being pivotally connected at one end to a bracket 26c secured to the window frame, and at its other end to a pair of spaced ears 22c projecting from the rectangular shaped body 12c of a holding element E3. The element E3 is slidably mounted on the member M3 between a shoe 13c and wear plate 14c, and a pair of expansible springs 18c seated in pockets 17c in the body 12c and interposed between washers 19c and 20c urge the shoe into frictional engagement with the member M3.

Screws 21c are threaded into the body 12c and bear against the washers 20c for adjusting the tension of the spring so that the friction set up by the member M3 can be varied at will. Between the pockets 17c, the body 12c is threaded to receive a fastening screw 30, the screw having an operating handle 31 by which it can be manually rotated into engagement with the shoe 13c so as to cause the latter to be moved into firm engagement with the member M3. The window can thus be firmly held against manual movement as well as movement by the wind. When the screw 30 is rotated to release it from the shoe, its movement is limited by a stop lug 32 projecting upwardly from the body 12c and disposed in the path of the handle 31, to the end that the handle cannot be rotated into engagement with the window where it would be difficult to grasp for subsequent manipulation. The position of the handle also serves to indicate whether the window is fastened or unfastened by the screw 30.

The embodiment of my invention shown in Figures 9 to 12, inclusive, is applied to the same type of window and in a manner identical to the form shown in Figures

7 and 8, and differs from the latter in the construction of the holding element E4 which in the present instance comprises a rectangular body 12d slotted horizontally to receive the member M4 between a shoe 13d and a wear plate 14d, the body being bored vertically to provide a pair of spaced pockets 17d in which are received coiled expansible springs 18d interposed between washers 19d 5

10 and 20d. The washers 19d bear against the shoe 13d and the tension of the spring can be varied at will to vary the friction set up between the shoe and member M4 by screws 21d threaded into the body and engaging the washers 20d. The ends of the shoe and wear plate are provided with lateral projections 15d and 16d, respectively, which prevent endwise displacement of the two, and in addition the shoe is provided on its under side with 15 a pair of rounded projections 33 which are adapted to be seated under the action of the springs 18d in recesses 34 formed in the upper surface of the member M4 at intervals along its length corresponding to the spacing of the projections 33. The window will thus be frictionally held against movement, yet can be moved manually by applying sufficient pressure thereto to overcome the tension of the springs 18d and cause the projections 33 to be cammed by the curved surfaces of the recesses 34 upwardly onto the otherwise smooth upper surface of the member M4, the co-acting projections and recesses tending to retard the movement of the window 20 should a wind of exceptionally high velocity arise and overcome the friction set up between the element E4 and member M4. The seating of the projections in the recesses produces an audible click which indicates to one when adjusting the window that it is adjusted to a position from which it will not be dislodged by ordinary winds. However, for the purpose of positively fastening the projections 33 against movement from the recesses 34, a fastening abutment 35 is fixed to a stub shaft 36 journaled horizontally in the body 12d above the shoe 13d and extending through a flanged disk 37 seating in an opening 38 formed in the body. 25

30 A cotter pin 39 prevents displacement of the disk from the shaft 36, and an expansible coil spring 40 on the shaft, interposed between the abutment 35 and disk 37 sets up sufficient friction to maintain the shaft and 35 consequently the abutment in any position to which the shaft is adjusted by a handle 41 fixed to the projecting end of the shaft.

With the shaft rotated to the position shown in Figure 10, the abutment 35 will engage the upper surface of the shoe 13d so that upward movement of the latter to disengage its projections 33 from the recesses 34 will positively be prevented, thereby positively fastening the window against movement, the abutment being limited in its fas-

tening movement by a stop lug 42 projecting upwardly from the shoe as clearly shown in Figure 11. When it is desired to adjust the window the shaft 36 is rotated by the handle 41 to move the abutment 35 to the position shown in Figure 11, thereby permitting the shoe to be elevated against the tension of the springs 18d to disengage the projections 33 from the recesses 34. 70

I claim as my invention:

1. A regulating device of the character described comprising a bracket adapted to be secured to a closure frame, a guide bar, brackets secured at the ends of the guide bar and adapted to be secured to a swinging closure in the frame so as to support the bar in spaced relation to the closure, a holding element comprising a body slotted to receive the bar, a shoe in the slot of the body adapted to engage the bar at one side, a wear plate in the slot adapted to engage the opposite side of the bar, said body having a pocket, washers in the pocket, an expansible coil spring in the pocket and interposed between the washers for urging the shoe into engagement with the bar and the latter into engagement with the wear plate so as to set up friction between the element and the bar, a screw threaded into the body and engaging one of the washers by which the tension of the spring can be varied to accordingly vary the friction set up thereby, and a rigid rod pivotally connected to the body and to said first bracket for the purpose described. 95

2. A regulating device of the character described comprising a bracket adapted to be secured to a closure frame, a guide bar adapted to be secured to a swinging closure in the frame and provided with a series of recesses at intervals along its length, a holding element comprising a body slidably mounted on the bar, a shoe mounted in the body and movable laterally with respect to the length of the bar, projections on said shoe adapted to seat in the recesses of said bar, during movement of the element along the bar, means for urging the shoe towards the bar so as to yieldingly maintain said projections in engagement with the recessed surface of said bar, and a rigid member pivotally connected to the bracket and element so as to cause sliding movement of the latter when the closure is moved to effect seating of said projections in said recesses, whereby sufficient friction will be set up between the element and bar to resist movement of the bar under the action of wind, said urging means yielding upon the application of manual force to the closure so as to cause the shoe to be cammed away from the bar under co-action of said projections and recesses when the element is moved along the bar to thereby disengage the projections from the recesses. 110

3. A regulating device as embodied in claim 2 wherein means is provided for lock-

ing the shoe against lateral movement away from the bar so as to maintain said projections in engagement with said recesses and thereby positively lock the element against movement on the bar.

4. A regulating device of the character described comprising a bracket adapted to be secured to a closure frame, a guide bar adapted to be secured in spaced relation to a swinging closure in the frame, a holding element comprising a body slidably mounted on the bar, a shoe mounted in the body, means for urging the shoe into engagement with the bar so as to set up friction between the bar and element to resist sliding movement of the latter, a rigid rod pivotally connected to said bracket and element so as to cause sliding movement of the latter when the closure is moved, said shoe setting up sufficient friction to prevent movement of the closure under the action of the wind, yet yielding to manual pressure applied to the closure so that the latter can be adjusted at will, a stop member adapted to be engaged by the element so as to limit the opening movement of the closure which is slidably mounted on the bar, and means for clamping the stop member against movement on the bar.

5. A regulating device of the character described comprising a bracket adapted to be secured to a closure frame, a guide bar adapted to be secured in spaced relation to a swinging closure in the frame, a holding element comprising a body slidably mounted on the bar, a shoe mounted in the body, means for urging the shoe into engagement with the bar so as to set up friction between the bar and element to resist sliding movement of the latter, a rigid rod pivotally connected to said bracket and element so as to cause sliding movement of the latter when the closure is moved, said shoe setting up sufficient friction to prevent movement of the closure under the action of the wind, yet yielding to manual pressure applied to the closure so that the latter can be adjusted at will, the element being provided with separate means manually operable to engage and move the shoe into firm engagement with the bar so as to fasten the element against movement on the bar.

6. In a regulating device of the character described, a holding element comprising a body having an opening through which a guide bar is adapted to extend, a shoe in the body adapted to engage the guide bar, the body having a socket therein extending laterally from the opening, washers in the pocket, an expansible coil spring in the pocket and interposed between the washers, for urging the shoe into engagement with the bar to set up friction between the element and bar, and means adjustable in the body and engaging one of the washers, by which the ten-

sion of the spring can be varied to thereby vary the friction set up by the shoe.

7. In a regulating device of the character described, a holding element comprising a body having an opening through which a guide bar is adapted to extend, a shoe in the body adapted to engage the guide bar, the body having a socket therein extending laterally from the opening, washers in the pocket, an expansible coil spring in the pocket and interposed between the washers, for urging the shoe into engagement with the bar to set up friction between the element and bar, means adjustable in the body and engaging one of the washers, by which the tension of the spring can be varied to thereby vary the friction set up by the shoe, and means in the body by which the shoe is adapted to be moved into firm engagement with the bar and thereby set up sufficient friction to fasten the element against movement on the bar.

8. In a regulating device of the character described, a holding element comprising a body having an opening therethrough in which a guide bar is adapted to be received, a shoe in the body adapted to engage one side of the bar, a wear plate in the body adapted to engage the opposite side of the bar, the body having a pocket therein extending laterally from the opening, and resilient means in the body by which the shoe is adapted to be urged into engagement with the bar and the latter into engagement with the wear plate so as to set up friction between the element and bar.

9. In a regulating device of the character described, a holding element comprising a body having an opening therethrough in which a guide bar is adapted to be received, a shoe in the body adapted to engage the opposite side of the bar, the body having a pocket therein extending laterally from the opening, resilient means in the body by which the shoe is adapted to be urged into engagement with the bar and the latter into engagement with the wear plate so as to set up friction between the element and bar, the body having a pocket extending laterally from the opening, washers in the pocket, an expansible coil spring in the pocket and interposed between the washers, for urging the shoe into engagement with the bar and the latter into engagement with the wear plate, to set up friction between the element and bar, and means adjustable in the body and engaging one of the washers by which the tension of the spring can be varied to thereby vary the friction set up.

10. In a regulating device of the character described, a guide bar adapted to be secured to a closure, and a holding element comprising a body slidably mounted on the bar, a shoe mounted in the body and movable laterally with respect to the bar, means for urging the shoe towards the bar, co-acting means on

the shoe and bar operating under the action of said urging means to releasably retain the holding element in any one of a plurality of different definite positions along the length 5 of the bar, and means for positively maintaining the element in any one of said plurality of different definite positions.

11. In a regulating device of the character described, a guide bar adapted to be secured 10 to a closure, and a holding element comprising a body slidably mounted on the bar, a shoe mounted in the body and movable laterally with respect to the bar, means for urging the shoe towards the bar, and co-acting 15 means on the shoe and bar operating under the action of said urging means to releasably retain the holding element in any one of a plurality of different positions along the length of the bar, said co-acting means comprising a series of recesses along the length 20 of the bar, and projections on the shoe, engageable with said recesses to thereby set up sufficient friction under the action of said urging means to releasably retain the holding 25 element against movement on the bar, the urging means yielding to allow the shoe to be moved away from the bar under camming action of said projections against said recesses when sufficient force is exerted against 30 the element in the direction of its movement on the bar, to overcome the friction set up between the projections and recesses.

12. In a regulating device of the character described, a guide bar adapted to be secured 35 to a closure, and a holding element comprising a body slidably mounted on the bar, a shoe mounted in the body and movable laterally with respect to the bar, means for urging the shoe towards the bar, and co-acting 40 means on the shoe and bar operating under the action of said urging means to releasably retain the holding element in any one of a plurality of different positions along the length of the bar, said co-acting means comprising a series of recesses along the length 45 of the bar, and projections on the shoe, engageable with said recesses to thereby set up sufficient friction under the action of said urging means to releasably retain the holding 50 element against movement on the bar, the urging means yielding to allow the shoe to be moved away from the bar under camming action of said projections against said recesses when sufficient force is exerted against 55 the element in the direction of its movement on the bar, to overcome the friction set up between the projections and recesses, and means for latching the shoe against lateral movement away from the bar so as to maintain 60 said projections in engagement with said recesses and thereby positively latch the element to the bar.

13. In a regulating device of the character described, a guide bar adapted to be secured 65 to a closure, and a holding element comprising

ing a body slidably mounted on the bar, a shoe mounted in the body and movable laterally with respect to the bar, means for urging the shoe towards the bar, and co-acting means on the shoe and bar operating under the action of said urging means to releasably retain the holding element in any one of a plurality of different positions along the length of the bar, 70 said co-acting means comprising a series of recesses along the length of the bar, and projections on the shoe, engageable with said recesses to thereby set up sufficient friction under the action of said urging means to releasably retain the holding element against movement on the bar, the urging means yielding to allow the shoe to be moved away from the bar under camming action of said projections against said recesses when sufficient force is exerted against the element in the direction of its movement 75 on the bar, to overcome the friction set up between the projections and recesses, and means for latching the shoe against lateral movement away from the bar so as to maintain said projections in engagement with said recesses 80 and thereby positively latch the element to the bar, said last means comprising a stub shaft journaled in the body, a handle on the shaft for rotating the latter, and an abutment on the shaft adapted to engage the shoe. 85

14. In a regulating device of the character described, a guide bar adapted to be secured to a closure, and a holding element comprising a body slidably mounted on the bar, a shoe mounted in the body and movable laterally with respect to the bar, means for urging the shoe towards the bar, co-acting means on the shoe and bar operating under the action of said urging means to releasably retain the holding element in any one of a plurality of different positions along the length of the bar, said co-acting means comprising a series of recesses along the length of the bar, and projections on the shoe, engageable with said recesses to thereby set up sufficient friction under the action of said urging means to 100 releasably retain the holding element against movement on the bar, the urging means yielding to allow the shoe to be moved away from the bar under camming action of said projections against said recesses when sufficient force is exerted against the element in the direction of its movement on the bar, to overcome the friction set up between the projections and recesses, and means for latching the shoe against lateral movement away from the bar so as to maintain said projections in engagement with said recesses and thereby positively latch the element to the bar, and means for releasably retaining the shaft in a 105 selected position of rotational adjustment. 110

ERIC SODERGREN.
